UNITED STATES PATENT OFFICE.

FRANK H. POWERS, OF PETERSBURG, NEW YORK, ASSIGNOR TO CHARLES W. REYNOLDS AND DAVID H. KELLYER, OF SAME PLACE.

SHIRT.

SPECIFICATION forming part of Letters Patent No. 366,685, dated July 19, 1887.

Application filed June 17, 1886. Serial No. 205,397. (No model.)

To all whom it may concern:

Be it known that I, FRANK H. POWERS, of Petersburg, Rensselaer county, New York, have invented new and useful Improvements 5 in Shirts, of which the following is a specification.

My invention relates to the manner of making and cutting the blank forms from which shirts are produced; and it has for its object 10 to simplify the art, reducing the number of pieces, and to make the shirts more durable by reducing the number of seams by which the parts are put together.

My invention consists (as will be more fully 15 described hereinafter in connection with its illustration) in the combination, with a shirt-body having the usual back-slit opening, of a placket cut from the same material as the body, having the form of half of a yoke, half 20 of one side of a front re-enforce, and a facing for the overlap of the back-slit opening, and another placket-piece cut from the same material as the body, to have the form of the opposite half of the yoke, the opposite half of 25 the front re-enforce, and also the form required to make the outer facing of the slit underlap and the inner facing of the slit overlap.

Accompanying this specification, to form a 30 part of it, there are four plates of drawings, containing eight figures, illustrating my invention, with the same designation of parts by letter-reference used in all of them.

Of these illustrations, Figure 1 shows the completed shirt, with the bosom-front turned 35 toward the sight. Fig. 2 shows the shirt with the bosom, front re-enforce parts, and yoke parts connected, but with the sides not closed or sewed up or the sleeves put in. Fig. 3 shows a cross-section taken on the line $x' x'$ of Fig. 2. Fig. 4 shows a cross-section taken 40 on the line $x^2 x^2$ of Fig. 2; and Fig. 5 shows a cross-section taken on the line $x^3 x^3$ of Fig. 2. Fig. 6 shows a blank form or placket cut from the material in a single piece to produce one- 45 half of the yoke, one-half of the front re-enforce, and the outer facing of the overlap formed at one side of the back-slit. Fig. 7 shows a single piece or placket cut from the material to form an opposite half of the yoke, 50 an opposite half of the front re-enforce, and

the inner facing of the slit overlap and the outer facing of the slit underlap. Fig. 8 shows a modification, with the shirt-body cut in a single piece from the fabric.

The several parts of the shirt thus illustrated 55 are designated by letter-reference, and the method of connecting them is described as follows:

The letter S indicates the shirt-body, which may be made in a single piece, as shown at 60 Fig. 8, or made in two parts and united beneath the yoke-facing, as indicated by the dotted line $z z$ of Fig. 2.

The letter B designates the bosom, N the neck-opening, and d the usual back-slit. 65

The letter P' indicates a placket or piece cut from the fabric embodying the yoke-form Y' at one side of the neckband, between the latter and the sleeve-seam, embodying, also, one-half of the front re-enforce R' and the outer 70 facing, F', of the overlap O.

The letter P² designates another placket or piece cut from the material, to have the form Y² of half the yoke, the form R² of half the front re-enforce, and the form of the outer 75 facing, F², of the underlap U, and the inner facing, F', of the overlap, when said placket is folded transversely at m' .

The parts are connected as follows: The placket or piece P' is attached to the shirt-front between the bosom and the latter by stitching, (indicated at a'), and on its curved lines to the shirt-body at the front at a' , and at the sides of the said placket-piece P', within the sleeve-seams D'. At the back of the shirt 85 said placket on its curved line is sewed to the shirt-body at a^3 , and at a^4 to the shirt-body, so as to overlap one side, e , of the back-slit d , to form the overlap, with the lower tab end, T, of said placket or piece P' also attached to 90 the shirt-body below the slit at a^5 .

The placket or piece P² is attached to the shirt-front between the bosom and the latter by stitching, (indicated at a^6), and on its curved line to the body, as indicated at a^7 , and laterally at the sleeve-seam D². This placket is attached on its vertical edge to the side a^8 of the slit d throughout the length of the latter to the shirt-body at a^9 , and is then folded transversely, as at m' of Fig. 7, turned up, and 100

sewed upon each edge to the inner face of the overlap O. As thus attached, the front re-enforce, the yoke, and the slit stay and facing are produced from but two pieces of material, 5 and several of the seams and connections usually made in shirts are avoided. By reducing the number of seams the chances of their ripping when worn is avoided. The usual gathers required at the back and front to give con- 10 tour to the yoke are just as well put in as where the yoke is made in separate pieces. By making the body in one piece an additional advantage is gained.

I am well aware that the yoke parts, the re- 15 enforce parts, and the facings for the overlap and underlap cut separately are old and well-known shirt parts, and that my invention is limited to cutting in continuity these parts from a single piece for each side of the shirt, 20 and thereby avoiding the production of the several seams which their union requires when cut separately.

Having thus described my invention, what I claim, and desire to secure by Letters Patent, 25 is—

1. The combination, with the shirt-body S, having the neck-opening N and back-slit d, of the placket P', in a single piece, having the yoke-form part Y', the re-enforce-part form

R', and the outer facing, F', of the overlap, 30 said placket being attached to the shirt-body, as described, and the placket or piece P' in a single piece, having the yoke-form part Y', the re-enforce part R', and the strip-form part F' of the outer facing of the underlap, and the 35 inner facing, F', of the overlap, and being attached to the shirt-body in the manner as and for the purposes set forth.

2. In a shirt, the combination, with the body S, having the back-slit d and neck-opening N, of the placket or piece P', in a single piece to form in continuity one side part of the yoke, one side part of the front re-enforce, and the outer facing of the slit overlap, and the placket or piece P' in a single 45 piece, to form in continuity the opposite side part of the yoke, the opposite side part of the front re-enforce, the inner facing of the slit overlap, and the outer facing of the slit underlap, with said placket-pieces attached to the 50 shirt-body, as shown and described.

Signed at Troy, New York, this 29th day of April, 1886, and in the presence of the two witnesses whose names are hereto written.

FRANK H. POWERS.
